(57) **CLAIM**

The ornamental design for a flask for perfume, as shown and described.

DESCRIPTION

FIG. 1 is a front perspective view of a flask for perfume, in accordance with the present invention;

FIG. 2 is a rear perspective view of the flask of FIG. 1;

FIG. 3 is a front elevational view of the flask of FIG. 1;

FIG. 4 is a side elevational view of the flask of FIG. 1 (the opposite side elevational view being a mirror image of that shown);

FIG. 5 is a top plan view of the flask of FIG. 1; and,

FIG. 6 is a bottom plan view of the flask of FIG. 1.
